UNITED STATES PATENT OFFICE.

STEPHEN J. CLULEE, OF ATTLEBORO, MASSACHUSETTS.

EYEGLASSES.

1,286,534.

Specification of Letters Patent.

Patented Dec. 3, 1918.

Application filed August 16, 1916. Serial No. 115,147.

To all whom it may concern:

Be it known that I, STEPHEN J. CLULEE, a citizen of the United States, and a resident of Attleboro, in the county of Bristol and

5 State of Massachusetts, have invented an Improvement in Eyeglasses, of which the following is a specification.

This invention relates to eyeglasses. One of the objects thereof is to provide a simple 10 and practical construction for eyeglasses of highly efficient and dependable action. Another object is to provide a construction which shall be durable and in which the metal is economically used. Another object 15 is to provide a construction of the above type in which the parts are securely interlocked and yet readily assembled or taken apart. Other objects will be in part obvious and in part pointed out hereinafter.

20 The invention accordingly consists in the features of construction, combinations of elements, and arrangement of parts which will be exemplified in the construction hereinafter described, and the scope of the application of which will be indicated in the following claims.

In the accompanying drawing, in which is shown one or more of various possible embodiments of several features of this invention,

Figure 1 is a rear view of a guard arm mounting and associated parts;

Fig. 2 is a top plan of the parts shown in Fig. 1;

35 Fig. 3 is a detailed sectional elevation taken on the line 3—3 of Fig. 2 and showing the parts on a larger scale;

Fig. 4 is a bottom plan view of a portion of Fig. 1;

40 Fig. 5 is a detailed rear elevation of a portion of another form of eyeglasses;

Fig. 6 is a top plan view of the parts shown in Fig. 5;

45 Fig. 7 is a detailed sectional elevation taken on the line 7—7 of Fig. 6 and showing the parts on a larger scale.

Similar reference characters refer to similar parts throughout the several features of the drawing.

50 Referring now to Fig. 1 of the drawings there is shown an eyeglass lens 10, but it may here be noted that the term "eyeglasses" is used throughout in a broad sense to denote any device for supporting a lens for the eye.

55 The lens 10 is embraced in a lens clamp

11 of the ordinary form comprising the strap 12 and side lugs 13 secured one to another by the screw 14 passing through the lens.

Formed on or secured to the lens clamp 60 11 is a bearing portion or field 15 which merges into the bridge 16. It is to be understood that the parts at the opposite side of the bridge are substantially identical with those herein described and these parts are 65 not shown in duplicate or separably described herein, as it is desired to avoid encumbering this description in the accompanying drawing.

Passing through the part 15 and preferably rigidly secured therein is a sleeve 17 which extends materially above and below the former part. This sleeve is internally threaded for the purpose hereinafter described and is provided at its lower end with 75 a flange 18 and slot 19.

Mounted upon the field part 15 as a support is a swinging guard arm or lever 20 having jointed to its inner end a nose pad or guard 21. The outer end of this guard 80 arm is formed into a finger piece 22 by which the parts are swung into the position indicated at dotted lines at 23 in Fig. 2 of the drawings, as for the purpose of placing the eyeglasses upon the face or removing 85 them therefrom. This guard arm, which is broken away in Fig. 1 of the drawings to

show the construction more clearly, is pivotally mounted about the upper end of the sleeve 17. The opening 24 in the guard arm, 90 which may be assumed to be of the gold-filled construction, is formed by first making a small perforation and thereafter forcing the metal away from the plane of the body portion of the arm. By this action there is 95 formed a flange 25 which, even with the gold-filled constitution of the guard arm offers gold as a bearing metal upon all of its surfaces. This arrangement is highly 100 advantageous as the gold forms a far better bearing metal than the base metal which it incloses and is also less subject to corrosion.

The inner gold surfaces of the guard arm at 26 fit snugly the outer cylindrical surface of the sleeve 17 and provide a tubular bearing of considerable length, thus permitting for a given stability of the bearing a smaller engaging surface at 27 between the bottom of the guard arm and the top of the field portion 15. Furthermore, the upright flange 110

25 materially strengthens in a transverse direction the guard arm and for a given strength permits the latter to be narrowed at its pivotal engagement with the eyeglass frame, and thus permits a corresponding shortening of the field portion 15 and consequently permits the lenses to be brought closer together.

Threaded into the sleeve 17 is a screw 28 10 which fits snugly upon the top of the sleeve and over the flange 25 and is provided with a depending annular shoulder 29, embracing the flange and resting evenly on its lower surface upon the guard arm. This screw 15 not only securely locks the parts in position but greatly increases the surface of the bearing and by its engagement with the guard arm further strengthens the latter against breakage at its pivotal point. It will be 20 seen, moreover, that by the above described arrangement it is difficult for dirt to work into the bearing, as, even though it enters between the flange 29 and the guard arm, it cannot pass upwardly over the part 25.

25 Fitted within the slot 19 at the lower end of the sleeve 17 is one end of a flat coiled spring 30, the free end of which engages as at 31 and interlocks with the lower end of the short arm 32, extending downwardly 30 from the guard arm. This spring tends to swing the guard or nose pad 21 inwardly from the nose for a distance limited by the engagement of the stop shoulder 33 with the lens clamp 11.

35 The method and use of this form of eyeglasses will be clear from the above description and it will be seen that in this construction the several objects of this invention are achieved.

40 In Fig. 5 of the drawings there is shown a construction in which the lens clamp 11 is connected with the bearing portion or field piece 34 with a bridge 35, these parts being closely similar to those above described. There is threaded downwardly into the part 34 a screw 36 provided with a portion 37 of enlarged diameter. The opening in the part 34 into which the screw 36 is threaded is enlarged to provide an annular 45 recess 38 into which fits a flange 39 on the guard arm 40. This guard arm is provided at one end with the usual nose pad 41 and at the opposite end with the finger piece 42, whereby it may be swung in the customary manner and for the well-known purpose. The guard arm is urged into the inner operating position indicated in full line in Fig. 6 of the drawings by a spiral spring 43, one end of which interlocks with the lens 50 clamp and the other end of which is bent upon the rear surface of the guard arm, as indicated at 44. This spring is securely supported about the portion 37 of the screw 36 and yet may be readily removed, as for renewal, by withdrawing this screw. The

shoulder 45 formed by the portion 37 of the screw rests snugly upon the upper surface of the guard arm and not only increases the bearing surface of the latter but securely locks it in position. It is to be especially 70 understood that the flange 38 on the guard arm is made as above described by turning the metal downwardly from the original blank of the guard arm in such a manner as to preserve the continuity of the gold upon 75 all its exposed surfaces, even though this part be of the so-called gold-filled construction.

It will be seen that in the construction last described many of the features and advantages first set forth are embodied.

As various possible changes might be made in the above construction and as this invention might be embodied in various apparently different forms, it is to be understood that all matter herein described or shown in the accompanying drawings is to be interpreted as illustrative and not in a limited sense.

I claim as my invention:

1. In eyeglass construction, in combination, a bridge, a supporting portion adjacent an end of said bridge, a tubular bearing part extending from said supporting portion in a direction substantially parallel to the plane of the glasses, a lever provided with an opening fitted about said bearing and having an annular flange about said opening, and a screw entering said tubular member and engaging said lever to hold it in position.

2. In eyeglass construction, in combination, a bridge, a supporting portion adjacent an end of said bridge, a tubular bearing part extending from said supporting portion in a direction substantially parallel to the plane of the glasses, a lever provided with an opening fitted about said bearing and having an annular flange about said opening, and a screw entering said tubular member and engaging said lever to hold it in position, 105 the head of said screw being provided with an annular recess to receive said flange.

3. In eyeglass construction, in combination, a bridge, a supporting portion adjacent an end of said bridge, a tubular bearing part extending from said supporting portion in a direction substantially parallel to the plane of the glasses, a lever provided with an opening fitted about said bearing and having an annular flange about said opening, and a screw entering said tubular member and engaging said lever to hold it in position, 115 said flange bearing against said tubular member and being engaged by the head of said screw.

4. In eyeglass construction, in combination, a bridge, a supporting portion adjacent an end of said bridge, a tubular bearing part extending from said supporting portion in a direction substantially parallel 125

to the plane of the glasses, a lever provided with an opening fitted about said bearing and having an annular flange about said opening, and a screw entering said tubular member 5 and engaging said lever to hold it in position, the head of said screw being shaped to embrace said flange and extending downwardly to bear against the body of said lever.

5. In eyeglass construction, in combination, a bridge portion, a supporting portion adjacent the end of said bridge portion, a lever provided with an opening with an annular flange about said opening and securing means against which said opening and 10 flange form a bearing and provided with a head resting against the upper surface of said flange, said head having an annular recess within which said flange fits.

6. In eyeglass construction, in combination, a lens clamp, a bridge, bearing means interposed between said lens clamp and said bridge, a perforated guard arm having an annular shoulder or flange extending about its perforation and in the direction thereof, 15 said guard arm being pivotally mounted upon said bearing means with its upper and lower surfaces and the outer surface of said extension in contact with and bearing against said bearing means, and a spring 20 tending to swing said guard arm in a predetermined direction.

7. In eyeglass construction, in combination, a lens clamp, a bridge, supporting means interposed between said lens clamp 25 and said bridge, a screw provided with an annular recess, and a guard arm pivotally mounted upon said supporting means and formed to interlock with the recess of said screw.

8. In eyeglass construction, in combination, a lens clamp, a bridge, supporting means interposed between said lens clamp and said bridge, a guard arm provided with a perforation and an upwardly directed annular flange about said perforation, and a screw provided with a depending flange embracing the flange of said guard arm.

9. In eyeglass construction, in combina-

tion, a lens clamp, a bridge, supporting means interposed between said lens clamp 50 and said bridge, a sleeve passing through said supporting means, a guard arm provided with a perforation, and an annular flange by which said perforation is extended, said guard arm being fitted about said sleeve, 55 a screw threaded into the inner surface of said sleeve and provided with a depending flange on its head embracing the annular extension of said guard arm and a spring tending to swing said guard arm.

10. In eyeglass construction, in combination, a lens clamp, a bridge, supporting means interposed between said lens clamp and said bridge, a sleeve passing through 60 said supporting means, a guard arm provided with a perforation and an annular flange by which said perforation is extended, said guard arm being fitted about said sleeve, a screw threaded into the inner surface of said sleeve and provided with a depending flange on its head embracing the annular extension of said guard arm, a spring tending to swing said guard arm, 65 said guard arm being of gold-filled construction and having said annular extension 70 forced upwardly from its body portion with the gold extending over substantially its entire bearing surface.

11. In eyeglass construction, in combination, a bridge, a supporting portion at each 80 end of said bridge, an annular bearing part extending upwardly from each of said supporting portions, a pair of levers, each provided with an opening surrounded by an annular flange, said openings and flanges 85 respectively fitting and bearing on said annular portions and a pair of screws respectively threaded downwardly through said annular portions and provided with heads having annular recesses embracing said tubular portions and said flanges.

In testimony whereof I have signed my name to this specification this ninth day of August, 1916.

STEPHEN J. CLULEE.
